WIRES DRAWING BLOCK

Stephen J. Facht, New Haven, Conn.

Application May 14, 1945, Serial No. 593,613

6 Claims. (Cl. 205—20)

1

This invention relates to an improved stripper block for drawing wire.

One of the objects of the invention is the provision of a stripper block in which the stripper pins are locked in position by means of an improved locking means.

A further object of the invention is the provision of an improved stripper block which is simple and inexpensive in its construction and which is efficient, effective, and safe in its use.

These and other objects of the invention will become more fully apparent in the following specification.

The invention will be more readily understood by reference to the accompanying drawings, in which:

Figure 1 is a plan view of the stripper block of the present invention with one of the stripper pins removed from its position therein;

Figure 2 is a view in vertical section through the stripper block, the section being taken along the line II—II in Figure 1; and

Figure 3 is a view in horizontal section through a portion of the stripper block at one of the stripper pins, said section being taken along the line III—III in Figure 2.

In the patent to Zettergren, No. 2,327,149, dated August 17, 1943, there is disclosed a wire drawing stripper block provided with locking means for retaining the stripper pins therein. In the Zettergren construction, such locking means is in the nature of a bayonet lock, there being a vertical slot in the side wall of the stripper pin receiving hole in the block to receive a projecting lug on the stripper pin, such vertical slot being connected at the bottom thereof with an L-shaped slot so that the lug on the pin may be received in the end of the L-slot when the stripper pin is pressed downwardly against the spring in the pin receiving hole and is turned in the proper direction. Although such bayonet locking means has proved to retain the stripper pins satisfactorily during operation of the stripper block, it has been found somewhat difficult to operate and the drawing block incorporating it has been expensive to manufacture. When the stripper pin is inserted in the hole in the stripper block it must be turned until the lug enters the vertical slot. Furthermore, once in the hole the pin must be turned in the right direction so that the lug enters the L-shaped slot in order to lock it in the block. Both such operations are bothersome and time consuming. Furthermore, the machining of the vertical slot and the L-shaped slot in the side wall of the pin receiving hole in the stripper

2

block must be carefully done and involves the use of special tools, thus adding considerably to the total cost of the stripper block.

The improved stripper block of the present invention employs a locking means of such character that the stripper pins may be inserted into the hole therein in any angular relationship and in which the pin may be locked when inserted to its full depth by being turned, if necessary, in either direction. Furthermore, because of its simplicity and because it necessitates only a simple cutting operation on the block, which may be performed from outside the pin receiving openings, the use of such improved locking means adds but little to the total cost of a stripper block.

Referring more particularly to the drawings, the improved wire drawing block of my invention consists of a circular stripper block 2 having a smaller circularly arranged flange portion 4 disposed on one side thereof. The stripper block is provided with a central hole 6 having a longitudinally extending key-way 8 in the wall thereof. A shaft 10 is adapted to be inserted in the hole 6 and to be keyed thereto by means of a key 12 in the key-way 8.

Around the flange portion 4 of the stripper block 2 there is disposed a plurality of equally spaced semi-circular bosses 14, as shown in Figure 1. Each boss is provided with an upright hole 16 for the reception of the lower end of a stripper pin 18, the upper end of which is provided with an enlargement to prevent the escape of wire thereover, such enlargement in the modification shown being provided by bending the upper end of the pin in the form of a ring 20.

The inner face of each of the bosses 14 is provided with a horizontal slot 22 as shown in Figure 2. Such slot may be easily made by the use of a milling tool with its axis parallel to the axis of shaft 10. Slots 22 receive locking ring 24 which is formed of flat stock bent into the form of an open ring. Ring 24 is retained in its outward position by means of compression spring 26 which is received over the open ends of the ring and is held under compression by means of bolts 28 through the ends of the ring.

Each stripper pin 18 is provided, as shown in Figures 2 and 3, with two opposite flattened portions 30, at a location an appropriate distance from the bottom of the pin, and with a conical lower end 32. Such construction allows the easy introduction of a stripper pin into the block, the locking thereof, and the unlocking and removal of the pin in a manner which is correspondingly simple. Pin 18 is inserted into a vacant hole

16, without regard to its angular disposition, and is then thrust downwardly, until the tip of end 32 contacts the lower end of the hole 16. Should it happen that the pin is in a correct position angularly so that one of the flattened portions 32 confronts the spring ring 24, the ring will snap into the flattened portion and the pin will be automatically locked. If, however, pin 18 is inserted with such angular disposition that the ring 24 rides up over point 32 and onto the rounded portion 34 between the slots 30, it will be necessary to turn pin 18 either to the right or to the left until one of the flattened portions 30 confronts the spring ring so that the ring falls into the slot and locks the pin.

Removal of the pin when so locked is accomplished by turning the pin a quarter turn so that the spring ring 24 rides up onto the rounded portion 34. The pin then may be removed merely by pulling it axially from hole 16. It will be appreciated from the above description that the locking means of my improved stripper block results in greatly simplified operations in its insertion, locking, unlocking, and withdrawal and that construction of the block is much simpler than those of prior art devices.

Having thus fully disclosed the manner of construction and operation of my improved wire drawing block, I desire to claim as new the following.

I claim:

1. A wire drawing block comprising a wire receiving body rotatable about an axis, the body having a plurality of holes directed generally parallel to the axis of rotation of the block and arranged therein on one side thereof on a circle concentric with the axis of rotation of the body, a plurality of removable pin-like members with one adapted to be disposed in each of said holes, each of said pin-like members having means on the bottom portion thereof cooperating with means adjacent the bottom of the hole in the body selectively to lock the pin-like member in the body or to release it therefrom, said locking means comprising at least one open sided socket in each pin-like member and a spring-pressed locking ring for reception into the sockets in the members, said locking ring being supported coaxially on the body of the wire drawing block so as to be held from movement axially of the body and so that portions of it lie in the paths of the pin-like member in the holes in the absence of such members, the locking ring having peripheral and bottom surfaces shaped for interaction with the sockets in the pin-like members to lock such members in the holes.

2. A wire drawing block comprising a wire receiving body rotatable about an axis, the body having a plurality of holes directed generally parallel to the axis of rotation of the block and arranged therein on one side thereof on a circle concentric with the axis of rotation of the body, a plurality of removable pin-like members with one adapted to be disposed in each of said holes, each of said pin-like members having means on the bottom portion thereof cooperating with means adjacent the bottom of the hole in the body selectively to lock the pin-like member in the body or to release it therefrom, said locking means comprising at least one open sided socket in each pin-like member, said socket having a bottom wall which lies at least substantially in a plane at right angles to the axis of the member, and a spring-pressed locking ring for reception into the sockets in the members, said locking

ring being supported coaxially on the body of the wire drawing block so as to be held from movement axially of the body and so that portions of it lie in the paths of the pin-like member in the holes in the absence of such members, the locking ring having a bottom surface lying at least substantially in a plane at right angles to the axes of the holes for interaction with the bottom walls of the socket in the pin-like members to lock such members in the holes.

3. A wire drawing block comprising a wire receiving body rotatable about an axis, the body having a plurality of holes directed generally parallel to the axis of rotation of the block and arranged therein on one side thereof on a circle concentric with the axis of rotation of the body, a plurality of removable pin-like members with one adapted to be disposed in each of said holes, each of said pin-like members having means on the bottom portion thereof cooperating with means adjacent the bottom of the hole in the body selectively to lock the pin-like member in the body or to release it therefrom, said locking means comprising at least one open sided socket in each pin-like member, said socket having a bottom wall which lies at least substantially in a plane at right angles to the axis of the member, and a spring-pressed locking ring for reception into the sockets in the members, said locking ring being supported coaxially on the body of the wire drawing block so as to be held from movement axially of the body and so that portions of it lie in the paths of the pin-like member in the holes in the absence of such members, the locking ring having a bottom surface lying at least substantially in a plane at right angles to the axes of the holes for interaction with the bottom walls of the socket in the pin-like members to lock such members in the holes, the spring-pressed locking ring comprising an open ended ring of rectangular cross section, a compression spring acting between the ends thereof, and means on the ends of the ring between which the spring acts to urge the ring to expanded condition.

4. A wire drawing block comprising a wire receiving body, said body having a bottom portion of generally disc-shape and an upper portion in the form of a circular flange affixed to the disc-shaped lower portion and concentric therewith, the body being rotatable about an axis concentric with the upper and lower portions thereof, a plurality of bosses spaced about the inner surface of the circular flange, each boss being provided with a hole therein generally parallel to the axis of the flange, each boss having a horizontal slot through its inner face communicating with the hole therein, the slots in the several bosses lying in a plane transverse to the axis of rotation of the body, a plurality of removable pin-like members with one adapted to be disposed in each of said holes in the bosses, each of said pin-like members having means on the bottom portion thereof cooperating with means adjacent the bottom of the hole selectively to lock the pin-like member in the body or to release it therefrom, said locking means comprising at least one open sided socket in the pin-like member, said socket having a bottom wall which lies at least substantially in a plane at right angles to the axis of the member, and a spring-pressed locking ring extending into each of the slots in the bosses for reception into the socket in the member in each hole, said locking ring being so disposed as to lie in the paths of the pin-like members in the holes in the absence of such members, the locking ring

having a bottom surface lying at least substantially in a plane at right angles to the axes of the holes for interaction with the bottom walls of the socket in the pin-like members to lock such members in the holes.

5. A wire drawing block comprising a wire receiving body, said body having a bottom portion of generally disc-shape and an upper portion in the form of a circular flange affixed to the disc-shaped lower portion and concentric therewith, the body being rotatable about an axis concentric with the upper and lower portions thereof, a plurality of bosses spaced about the inner surface of the circular flange, each boss being provided with a hole therein generally parallel to the axis of the flange, each boss having a horizontal slot through its inner face communicating with the hole therein, the slots in the several bosses lying in a plane transverse to the axis of rotation of the body, a plurality of removable pin-like members with one adapted to be disposed in each of said holes in the bosses, each of said pin-like members having means on the bottom portion thereof cooperating with means adjacent the bottom of the hole selectively to lock the pin-like member in the body or to release it therefrom, said locking means comprising at least one open sided socket in the pin-like member, said socket having a bottom wall which lies at least substantially in a plane at right angles to the axis of the member, and a spring pressed locking ring extending into each of the slots in the bosses for reception into the socket in the member in each hole, said locking ring being so disposed as to lie in the paths of the pin-like members in the holes in the absence of such members, the locking ring having bottom surfaces lying at least substantially in a plane at right angles to the axis of the holes for interaction with the bottom walls of the socket in the pin-like members to lock such members in the holes, the spring-pressed locking ring comprising an open ended ring of a rectangular cross section, a compression spring acting between the ends thereof, and means on the ends of the ring between which the spring acts to urge the ring to expanded condition.

6. A wire drawing block comprising a wire receiving body, said body having a bottom portion of generally disc-shape and an upper portion in the form of a circular flange affixed to the disc-shaped lower portion and concentric therewith, the body being rotatable about an axis con-

centric with the upper and lower portions thereof, a plurality of bosses spaced about the inner surface of the circular flange, each boss being provided with a hole therein generally parallel to the axis of the flange, each boss having a horizontal slot through its inner face communicating with the hole therein, the slots in the several bosses lying in a plane transverse to the axis of rotation of the body, a plurality of removable pin-like members with one adapted to be disposed in each of said holes in the bosses, each of said pin-like members having means on the bottom portion thereof cooperating with means adjacent the bottom of the hole selectively to lock the pin-like member in the body or to release it therefrom, said locking means comprising at least one open sided socket in the pin-like member, said socket having a bottom wall which lies at least substantially in a plane at right angles to the axis of the member, and a spring-pressed locking ring extending into each of the slots in the bosses for reception into the socket in the member in each hole, said locking ring being so disposed as to lie in the paths of the pin-like members in the holes in the absence of such members, the locking ring having bottom surfaces lying at least substantially in a plane at right angles to the axis of the holes for interaction with the bottom walls of the socket in the pin-like members to lock such members in the holes, the spring-pressed locking ring comprising an open ended ring of a rectangular cross section, a compression spring acting between the ends thereof, and means on the ends of the ring between which the spring acts to urge the ring to expanded condition, the slots in each boss being of substantially the same height, the locking ring being of such height as to fit closely within such slots.
